(57) **CLAIM**

The ornamental design for a sleeveless coaxial cable connector in closed position, as shown and described.

DESCRIPTION

FIG. 1 is a top perspective view of a sleeveless coaxial cable connector in closed position showing our new design;
FIG. 2 is a side elevation view thereof;
FIG. 3 is a front elevation view thereof; and,
FIG. 4 is a rear elevation view thereof.
The portions inside the connector shown in broken lines in FIG. 4 form no part of the claimed design.
